FITTING FOR USE WITH GLAZING BARS

Jack Williams, London, England

Application December 12, 1938, Serial No. 245,309
In Great Britain February 1, 1938

7 Claims. (Cl. 108—16)

This invention relates to fittings for use with glazing bars of the kind comprising a web having projections laterally therefrom a longitudinally extending flange-like abutment, on one face 5 of which the glass bears and with which it is held in engagement by a resilient clamping bar which extends in a generally inclined direction from the point where it engages the web into contact with the other face of the glass. As a 10 rule such glazing bars comprise a central web the base of which has a glass-supporting abutment on either side and in addition an outer flange lying outside each glass-supporting abutment and extending towards but not into contact with the glass.

The object of the present invention is to provide a convenient form of stop to engage the end of the glass which generally extends a short distance beyond the bearer, purlin or other longitudinal support for the glazing bar, and further to provide a cheap and convenient means by which the bar can be secured to its bearer.

According to this invention the glass stop for use with a glazing bar of the above type comprises a substantially L-shaped strip adapted to engage the under side and end of the glazing bar and to be secured to the bearer which supports the glazing bar. Preferably the stop comprises a single unit, of which the shank portion, adapted 25 to engage the under side of the glazing bar, is secured to the bearer by means of a shoe and this shoe is so constructed that it not only engages the shank of the glass stop, so as to hold it in position on the bearer, but also engages the flanged lower edges of the glazing bar so as to hold it 30 down on the shank of the stop.

In the preferred construction the shoe comprises a base plate having two curved arms, the ends of which are provided with inturned flanges. 40 The shank of the stop has its longitudinal edges slotted so as to engage the upper face of the base plate between the arms, and the arrangement is such that after the base plate has been secured to the bearer for the bar, the shank of 45 the stop is placed in position and the end of the glazing bar is then slid into position so that the flanged ends of the arms of the shoe engage the edges of the outer flanges at the base of the glazing bar. The shank of the stop is thus gripped between the flanged edge of the bar and 50 the fixed shoe, and the upturned end of the stop will engage the web of the glazing bar when the latter is slid home. In this way, by means of a 55 single shoe secured to the bearer, both the glass stop and the bearer itself are locked in position.

The invention may be carried into practice in various ways but one construction according to the invention and a modification thereof are illustrated by way of example in the accompanying drawing, in which

Figure 1 is a side elevation of one construction showing the glass and bearer in cross-section,

Figure 2 is a section on the line 2—2 of Figure 1,

Figure 3 is a section on the line 3—3 of Figure 1, and

Figure 4 is a similar view to Figure 2 of the modified construction.

In the construction illustrated in Figures 1, 2 and 3, the fitting is shown as applied to a glazing bar assembly of the kind forming the subject of the present applicant's copending United States of America patent application Serial No. 224,957, comprising a central web portion A having a flange A¹ at its base provided with upturned rib-like parts A² adapted to act as abutments on which the under surface of sheets of glass B rest and with upturned flange-like edges A³.

Rib-like projections A⁴ having grooves there-in constitute anchorages for the upper edges of resilient clamping strips C which bear on the upper surfaces of the sheets of glass B to maintain them in contact with the abutments A². The parts of the glazing bar assembly shown are generally made by extrusion from aluminum or other non-corrosive alloy.

In use the bar is connected within a short distance of its outer or lower end to a bearer such as the bearer D shown, the end of the bar projecting a short distance beyond the bearer and the stop according to the invention not only serves to hold the bar from movement away from the bearer D but also to prevent the bar and glass from moving in a direction parallel to the length of the bar or parallel to the length of the bearer.

Thus, the stop comprises a substantially L-shaped unit E having a shank portion E¹ which lies below and parallel to the length of the glazing bar and between the flange A¹ and the bearer D, and an upturned end portion E² against which the glass B and the end of the bar A bears, this upturned end portion being provided with two inturned fingers E³ lying one on each side of the web A.

As will be seen, the under side of the shank portion E¹ is provided with ribs E⁴ so as to leave a clearance space between the central portion of the shank E¹ and the bearer D.

The unit E is connected to the bearer D by a shoe comprising a base F passing beneath the shank portion E¹, and curved arms F¹ the ends of which are inturned, as shown at F², to engage the edges of the parts A³. The internal shape of the arms F¹ conforms approximately to the curvature of the parts A³ and the ribbed sides of the shank portion E¹ of the unit E are cut away or slotted, as shown to receive the arms F¹. The base F is secured as by screws F⁵ to the bearer D.

It will thus be seen that the combined stop and

shoe comprises only two parts which can readily be manufactured and yet serve to connect the bar A to the bearer D in a manner preventing the bar sliding outwards and downwards and holding the bar from movement away from or parallel to the length of the bearer D while also acting as a stop to prevent the glass B sliding outwards and downwards.

In the modified construction illustrated in Figure 4, the form of the bar A, the L-shaped stop unit E and the manner in which these two parts cooperate, is the same as in the construction shown in Figures 1, 2 and 3. In the construction shown in Figure 4, however, the shoe, instead of being constructed as shown in Figures 1, 2 and 3, is provided with a trough-like base F⁶ in which lies the head of a bolt F⁷ adapted to pass through a bearer D¹, for example of metal, so as to secure the shoe F⁶ to the bearer D¹. The trough-like base is provided with a shoulder F⁸ on which rests the part E¹ of the unit E so that this part lies between the shoulder and the flange A¹ of the bar A. The ribbed sides E⁴ of the part E¹ of the unit E are provided with slots through which the arms F¹ of the shoe extend, as in the construction shown in Figures 1, 2 and 3, these arms being provided with inturned edges F² adapted to engage the edges of the parts A³. In this construction it will be seen that the part E¹ of the unit E is supported by the shoe F⁶ out of contact with the bearer D¹.

It will be obvious that the invention is not limited to use with glazing bars having the particular cross-section shown in the drawing and that minor constructional features may be varied without departing from the invention.

What I claim as my invention and desire to secure by Letters Patent is:

1. A glass stop for use with a glazing bar supported by a bearer and having a flange on its lower edge, including in combination an L-shaped strip the shank and upturned end of which are adapted to engage respectively the under side of the flange and the end of the glazing bar, and a shoe adapted to be secured to the bearer and on which the shank of the L-shaped strip rests, the shoe having laterally extending arms which engage slots in the sides of the shank and are provided with inturned ends which engage the edges of the flange to secure the flange to the shank of the L-shaped strip and to the shoe.

2. A glass stop for use with a glazing bar supported by a bearer and having a flange on its lower edge, including in combination an L-shaped strip the shank and upturned end of which are adapted to engage respectively the under side of the flange and the end of the glazing bar, and a shoe adapted to be secured to the bearer and on which the shank of the L-shaped strip rests, the shoe having laterally extending arms which engage slots in the sides of the shank and are provided with inturned ends which engage the edges of the flange to secure the flange to the shank of the L-shaped strip and to the shoe, the shoe being provided with a groove in which lies the part of the shank of the L-shaped strip engaging the shoe so that the inner surface of the arms is substantially continuous with the upper surface of the said part of the shank.

3. A glass stop for use with a glazing bar supported by a bearer and having a flange on its lower edge, including in combination an L-shaped

strip the shank and upturned end of which are adapted to engage respectively the under side of the flange and the end of the glazing bar, and a shoe adapted to be secured to the bearer and on which the shank of the L-shaped strip rests, the shoe having laterally extending arms which engage slots in the sides of the shank and are provided with inturned ends which engage the edges of the flange to secure the flange to the shank of the L-shaped strip and to the shoe, the edge portions of the shank of the L-shaped strip being provided with downwardly extending ribs the under surfaces of which lie in the same plane as the under surface of the base of the shoe.

4. A glass stop for use with a glazing bar supported by a bearer and having a flange on its lower edge, including in combination an L-shaped strip the shank and upturned end of which are adapted to engage respectively the under side of the flange and the end of the glazing bar, and a shoe adapted to be secured to the bearer and on which the shank of the L-shaped strip rests, the shoe having laterally extending arms which engage slots in the sides of the shank and are provided with inturned ends which engage the edges of the flange to secure the flange to the shank of the L-shaped strip and to the shoe, the shoe being provided with a groove in which lies the part of the shank of the L-shaped strip engaging the shoe so that the inner surface of the arms is substantially continuous with the upper surface of the said part of the shank and the edge portions of the shank of the L-shaped strip being provided with downwardly extending ribs the under surfaces of which lie in the same plane as the under surface of the base of the shoe.

5. A glass stop for use with a glazing bar including the elements set forth in claim 1, in which the base of the shoe is provided with laterally extending lugs by which it can be attached as by screws to the bearer.

6. A glass stop for use with a glazing bar including the elements set forth in claim 1, in which the base of the shoe is formed with a recess in its upper surface lying below the flange of the glazing bar to accommodate the head of a bolt passing through the base of the shoe, whereby the shoe can be secured to the bearer.

7. A glass stop for use with a glazing bar supported by a bearer and having a flange on its lower edge, including in combination an L-shaped strip the shank and upturned end of which are adapted to engage respectively the under side of the flange and the end of the glazing bar, and a shoe adapted to be secured to the bearer and on which the shank of the L-shaped strip rests, the shoe having laterally extending arms which engage slots in the sides of the shank and are provided with inturned ends which engage the edges of the flange to secure the flange to the shank of the L-shaped strip and to the shoe, the shoe being provided with a groove in which lies the part of the shank of the L-shaped strip engaging the shoe so that the inner surface of the arms is substantially continuous with the upper surface of the said part of the shank and the base of the shoe being formed with a recess below the said groove to accommodate the head of a bolt passing through the base of the shoe, whereby the shoe can be secured to the bearer.

JACK WILLIAMS.
